MULTIPLE WAVE OSCILLATOR WITH SELF-
ADJUSTING GRID EXCITATIONAlexander Senauke, New York, N. Y., assignor to
AmpereX Electronic Products, Inc., Brooklyn,
N. Y., a corporation of New York

Application March 30, 1938, Serial No. 198,890

7 Claims. (Cl. 250—36)

This invention relates to oscillators, in the sense of power-driven oscillating circuits for generating oscillatory current, energized by a direct current source, or power frequency alternating current source, and to apparatus which is especially useful as a high frequency generator in diathermy machines, although, as will be understood, it may be employed under many other circumstances where an oscillator is desired which will furnish 5 oscillating current of a multiplicity of frequencies.

Among the objects of my invention may be mentioned the following:

To provide multiple-frequency generating apparatus in which the frequency of the oscillations generated may be selectively controlled by changing the constants of one circuit only of the apparatus; for example, in a circuit utilizing a tuned grid, tuned plate push-pull oscillator, by 10 changing the constants of the plate circuit only.

To provide means for automatically providing the proper degree or amount of grid excitation for any of a multiplicity of wave lengths (or frequencies) which may be desired in operation, as controlled by the wave length switch.

To provide oscillation generating apparatus which may be assembled and adjusted at the factory in such a manner that it is capable of operation by those unskilled in the manipulation and 15 adjustment of such apparatus, with the assurance that no technical problems will be encountered by them in the adjustment of the apparatus to various wave lengths and that the same will operate properly.

Still other objects and advantages of my invention will be apparent from the specification.

In this application I have particularly pointed out and distinctly claimed the part, improvement, or combination which I claim as my invention or discovery, and I have explained the principles thereof, and the best mode in which I have contemplated applying that principle, so as to distinguish it from other inventions.

In the drawing:

Fig. 1 is a circuit diagram of apparatus according to my invention for furnishing oscillations on either of two wave lengths as desired, and

Fig. 2 is a similar diagram of an oscillator for furnishing oscillations on any one of three wave 20 lengths.

Referring now to Fig. 1 of the drawing, I have illustrated a vacuum tube oscillator employing two vacuum tubes, preferably, although not necessarily, of the triode type connected in push-pull, the circuit being of the tuned grid, tuned

plate or so-called "TNT" type. Each of these tubes 1 and 2 respectively comprises a cathode, a control electrode and an anode illustrated as filamentary cathode 1a, grid 1b, and plate 1c in tube 1 and filament 2a, grid 2b and plate 2c in tube 2. The filaments may be connected together in parallel operation as indicated, and for simplicity I have omitted the filament heating source, the same being well known to the art.

The anode or plate 1c may be connected through inductance 3 to one terminal of inductance 5. Similarly the anode or plate 2c may be connected through inductance 4 to the other terminal of inductance 5, the mid-point of which may be connected to a suitable source of potential for energizing the plate circuit, herein indicated as 12.

The grid 1b may be connected through inductance 7 to a tuned circuit which may comprise inductance 10 and capacity 11, and the grid 2b may be connected through inductance 8 to the opposite side of said tuned circuit. The grid circuit may be completed by a connection from the mid-point of inductance 10 through resistance 9 to a point on the filament circuit.

The opposite terminals of inductance 5 may be connected to the terminals of a switch 13 by the operation of which the inductance 5 may be short circuited. The same is shown in diagrammatic form with an arrow indicating closure of 20 the switch to short circuit the said inductance. Preferably inductances 3 and 4 are both arranged at right angles with inductance 5 so as to have 25 minimum magnetic coupling therewith.

In case the tubes are of the simple triode type, 30 it will be understood that the feedback required to sustain oscillation takes place through the internal capacity of the tube and hence no separate feedback means is shown; although in case other types of tubes are employed, it will be understood that other forms of feedback circuits 35 may be employed such as are well understood in the art.

In diathermy machines it is ordinarily desirable to supply at least two frequencies of oscillation. The lower frequency may be, for example, in the neighborhood of 20 megacycles (15 meters), the higher frequency in the neighborhood of 50 megacycles (6 meters). In this case the values of 40 inductances 3, 4 and 5 will preferably be so chosen 45 that the natural frequency of the plate circuit with the tubes associated therewith is close to the desired lower frequency, this being a matter not necessary to be explained in detail to those skilled 50 in the art.

The grid circuit for maximum efficiency will preferably be tuned to a somewhat higher frequency than the plate circuit although not greatly higher, it being understood, as will be clear to those skilled in the art, that the grid circuit should have an inductive reactance of sufficient magnitude to produce the necessary grid voltage in the proper phase to keep the oscillatory circuit, which in this case is the plate circuit, in oscillation.

Considering the operation of the circuit, for example, at 15 meters, the switch 13 will be open and the inductances, 3, 4, and 5 will be included in the plate circuit. Since the switch 13 does not operate on the grid circuit in any way, the entire grid circuit will be included in either adjustment. It should be noted that the constants of inductances 7 and 8 are such that these coils alone are too small to provide the necessary excitation at 15 meters, but when added to the inductive reactance of the LC circuit formed by inductance 10 and capacity 11, the combined impedance is sufficient to give the necessary excitation; that is to say, neither coils 7, 8 or 10 (with condenser 11 in shunt with the latter) alone are sufficient to give the proper excitation at 15 meters. However, all together will afford such excitation, this result being obtained, by a proper choice of the values of inductances 7 and 8 and by choice of the values of inductance 10 and condenser 11 to supplement the reactance of inductances 7 and 8 at the lower frequency.

For operation at the higher frequencies the switch 13 may be closed, short-circuiting inductance 5, the value of inductances 3 and 4 being so chosen that the natural frequency of the plate circuit with inductance 5 short-circuited and with the tubes in circuit is now very close to the higher frequency desired, in this instance 50 megacycles. Under such circumstances, if the values of the inductance 10 and capacity 11 are properly chosen, capacity 11 will operate substantially as a by-pass around inductance 10, and, although the impedance of the LC circuit made up of inductance 10 and capacity 11 may be negative, that is to say, in the wrong phase to sustain oscillation, the impedances of the inductances 7 and 8 is in the proper phase and is made sufficient to compensate for the negative (in sign) impedance of the LC circuit, if such is the case.

I have found that very satisfactory results are obtained when the tubes 1 and 2 are of the type commercially available on the market as HF200, when inductances 7 and 8 have an inductance of 0.4 microhenry, when resistance 9 has the value of 5000 ohms, inductance 10 an inductance of 1.0 microhenry, condenser 11 a capacity of 50 micro-microfarads, inductances 3 and 4, 0.8 microhenry, and inductance 5, 9.0 microhenries.

With the apparatus shown and described, it will be clear that with the switch in position so that inductance 5 is not short-circuited, the oscillator will generate oscillations of lower frequency as determined by the constants of the plate circuit, and that the proper excitation will be supplied by the grid circuit, the inductive impedance of inductances 7 and 8 being supplemented by that of the LC circuit 10, 11. When the switch 13 is thrown in position to short-circuit the inductance 5, the constants of the plate circuit will be modified to cause a higher frequency to be generated, and in this instance the excitation again will be supplied in proper degree

by the grid circuit without change in any respect thereof. That is to say, by means of a simple short-circuiting switch in the plate circuit, it is possible to vary the constants thereof in a manner to determine the frequency of the oscillation to be generated, the frequency in either case being determined by the constants of the plate circuit and not by the grid circuit, and the grid circuit merely operating to maintain the necessary impedance of the proper sign (or phase), so that the plate voltage fed back to the grid, is of the correct phase and magnitude to maintain efficient oscillation.

It will be understood that while I have shown selecting the constants of the plate circuit by connection or short-circuiting of inductance, one may add or subtract capacity in parallel in the plate circuit for the purpose of controlling the constants thereof, as will be understood by those skilled in the art.

The same principle may be applied in oscillators designed to deliver oscillations of more than two frequencies. A circuit for this purpose is shown in Fig. 2 in which like reference numerals indicate like parts as in Fig. 1. In this instance the circuit is much the same as that of Fig. 1 except that an additional set of grid inductances 14 and 15 is provided, with condenser 16 connected between the common terminals of coils 14 and 7 and 15 and 8 respectively, and with an additional pair of coils 16 and 17 in the plate circuit. Connections are provided from the common point of coils 13 and 16 to switch contact 19, and from the common point of coils 4 and 17 to switch contact 20. In this instance switch 13 is indicated diagrammatically as being movable from neutral position to connect contacts 19 and 20 together in one position and to connect the other pair of contacts in the other position. The operation is the same in principle as already described for Fig. 1. In this instance, for example, it may be desired to generate oscillations of 80 meters, 15 and 6 meters, respectively, and the plate circuit constants are so chosen that when the switch 13 is in neutral position, the oscillatory plate circuit with the tubes associated therewith oscillates on the lowest frequency desired. The constants of the grid circuit are so chosen that proper grid excitation is supplied no matter what the position of the wave change switch 12. In this instance the inductances of coils 7, 14, 8 and 15 are insufficient to supply proper grid excitation at the lowest frequency and this lack of excitation is made up by the LC circuit of inductance 10 and capacity 11, which preferably is so chosen as to have a relatively high capacity and a relatively low inductance for the particular frequency desired.

When oscillations of the next higher frequency are desired, the wave change switch may be moved to the left to short-circuit inductance 5 and the frequency will now be determined by the constants of the plate circuit (with the tubes associated therewith) but not including inductance 5. Under this condition, the LC circuit 10, 11 being relatively high in capacity in effect provides nearly a short-circuit at the new higher frequency and the proper excitation is supplied for the same higher frequency by inductances 14 and 15, plus the effective impedance of the LC combination of inductances 7 and 8 shunted by condenser 16.

If the highest frequency is desired, the wave change switch 13 may be thrown to the right, thereby short-circuiting all of the plate induct-

ances except coils 16 and 17 and the frequency now generated will be determined by the constants of coils 16 and 17 with the tubes associated. At such frequency the condenser 18 acts substantially as a by-pass around inductances 7 and 8 and the excitation is furnished in effect by inductances 14 and 15.

It will be understood that the principle herein embodied may be applied to systems for generating a still greater number of frequencies, by increasing the number of sets of inductances and arranging the grid circuit so that at each increase in frequency a new condenser begins to act substantially as a by-pass at the higher frequency, reducing the amount of inductance previously effective in the grid circuit for producing excitation.

While I have shown and described the circuit as being of the push-pull type, so-called, or more strictly, the "push-push" type, and while this is the usually preferred form, it should be understood that my invention is not limited thereto, but may equally be employed in oscillating circuits of the tuned grid, tuned plate type employing only one tube, or a group of tubes in parallel. If only one tube or group of tubes is used, it will be found desirable to provide a by-pass condenser around plate source 12, as will be readily understood, and the natural frequency of the oscillatory plate circuit with the tube or tubes in place determines the frequency of oscillation, while the grid circuit constants are so chosen, as already described, as to afford proper excitation at the various frequencies without change of tuning in the grid circuit.

In the claims, I have used the term "oscillatory circuit" to designate the plate circuit, which is the driven circuit, and is maintained in oscillation at its own frequency (with the tubes associated therewith) and the term "control circuit" to designate the grid circuits, in the sense that the grid circuit controls the flow of plate current in the tubes, and not in the sense that the grid circuit controls the frequency of oscillation. This latter control is exercised primarily by the "oscillatory circuit".

The term "fixed tuned circuit" is used to designate a circuit which operates at a plurality of frequencies without change of constants.

While I have shown and described the preferred embodiment of my invention, it will be understood that modifications and changes may be made without departing from the spirit and scope of my invention.

I claim:

1. In an oscillation generating system, in combination, an oscillator comprising a space current path, said path including a frequency-determining oscillatory circuit, means for selectively controlling the constants of said oscillatory circuit to select the frequency of oscillation at one of a number of frequencies, a control circuit operating on said space current path, said

control circuit comprising a fixed tuned inductance-capacity circuit and inductance external to said fixed tuned circuit.

2. The combination claimed in claim 1, in which said inductance-capacity circuit has a natural frequency lower than that of said external inductance.

3. The combination claimed in claim 1, in which the impedance of said external inductance is insufficient to maintain oscillation of the system at the lowest selected frequency in the absence of said inductance-capacity circuit.

4. The combination claimed in claim 1, in which the impedance of said inductance-capacity circuit is insufficient to maintain oscillation of the system at the highest selected frequency in the absence of the said external inductance.

5. The combination claimed in claim 1, in which the impedance of said external inductance is insufficient to maintain oscillation of the system at the lower frequency in the absence of the inductance-capacity circuit, and in which the impedance of said inductance-capacity circuit is insufficient to maintain oscillation of the system at the higher frequency in the absence of said external inductance.

6. In an oscillation generating system, in combination, an oscillator comprising a space current path, said path including a frequency-determining oscillatory circuit, means for selectively controlling the constants of said oscillatory circuit to select the frequency of oscillation thereof at one of a number of frequencies, a control circuit operating on said space current path, said control circuit comprising a fixed tuned inductance-capacity circuit and fixed inductance external thereto, the constants of said fixed tuned circuit and said inductances being so chosen that excitation is supplied to maintain the system in oscillation at any of the desired frequencies while maintaining the control circuit constants unchanged.

7. In an oscillation generating system, in combination, an oscillator comprising a space current path, said path including a frequency-determining oscillatory circuit, means for selectively controlling the constants of said oscillatory circuit to select the frequency of oscillation at any one of several frequencies, a control circuit operating on said space current paths, said control circuit comprising a fixed tuned inductance-capacity circuit, an inductance external to said fixed tuned circuit, a condenser shunting said external inductance and fixed tuned circuit, and affording oscillation-sustaining excitation at one of the chosen frequencies, and by-passing said inductance and fixed tuned circuit at higher frequencies, and additional inductance in said control circuit, external to the circuit formed by said fixed tuned circuit, said first external inductance and said shunting condenser.

ALEXANDER SENAUKA.
